SUBSURFACE FLUID-OPERATED PUMP
Charles L. English, Tulsa, Okla.
Filed Mar. 18, 1960, Ser. No. 15,946
20 Claims. (Cl. 103—46)

This invention relates generally to improvements in fluid-operated pump units such as are used in producing oil wells, and more particularly, but not by way of limitation, to an improved fluid motor.

As it is well known in the oil producing industry, oil wells which have ceased flowing naturally are frequently produced by subsurface fluid-operated pump units. The fluid-operated pump unit is supported in the lower portion of an oil well and is energized by directing high pressure fluid, usually oil, from the surface downwardly through the well bore to the engine or motor end of the pump unit. The pump unit operates to force well fluids and exhausting power fluid upwardly through the well bore to the surface. Generally speaking, subsurface fluid-operated pump units have performed satisfactorily and possess several distinct advantages over the more conventional sucker rod type pumps which are mechanically actuated by a surface power unit and require a string of rods extending from the surface of the well downwardly to the subsurface pump. However, prior subsurface fluid-operated pumps have operated unsatisfactorily in some oil wells, which has prevented such pumps from being what may be considered universally accepted. For example, prior subsurface fluid-operated pump units have frequently operated unsatisfactorily in wells having a high gas-oil ratio. In such well conditions, the motor and pump pistons have a tendency to move with excessive speeds, and most prior pump units fail to make complete strokes in such gassy well conditions.

Most, if not all, present-day subsurface fluid-operated pumps include an engine or motor piston assembly having a main valve therein which controls the flow of high pressure fluid to either one or both ends of the motor cylinder and opens an exhaust passageway from at least one end of the motor cylinder when power oil is being supplied to the opposite end of the motor cylinder. These main valves are of various designs, but are reciprocally disposed in the piston assembly for a shifting movement as the piston assembly reaches or approaches the opposite ends of the motor cylinder. When the main valve is completely shifted from one of its operating positions to another, the flow of power oil and exhausting power oil is reversed to reverse the movement of the piston assembly. It will therefore be apparent that if the main valve is shifted prior to the completion of a stroke of the piston assembly, the piston assembly will still be immediately reversed. On the other hand, if the main valve is not shifted early enough, the piston assembly will tend to knock against the end of the motor cylinder and cause damage to the intricate pump construction. It may be noted that if the main valve tends to shift prior to the completion of the strokes of the piston assembly, the pump end of the device tends to "cavitate" in gassy wells, that is, the pump plunger will merely reciprocate in a gaseous medium and will not create sufficient suction in the pump cylinder to draw in oil from the well bore.

Basically, two types of valve mechanisms have been used to shift the main valve as a piston assembly reaches the end of its stroke, as well as hold the main valve in the desired position during a stroke of the piston assembly. In one type of valve mechanism, a single pilot valve extends from one end of the piston assembly and is slidably secured to one end of the motor cylinder, such that the pilot valve is mechanically shifted as the piston assembly reaches the end of either of its strokes. The pilot valve in turn controls the application of fluid pressures

2

on the main valve to hydraulically shift the main valve. When a single pilot valve of this type is used, the pilot valve is invariably subjected to varying fluid pressures, as well as varying frictional forces, when the pump unit is subjected to abnormal operations, such as in gassy well conditions. These various unpredictable forces on the pilot valve will frequently cause the pilot valve to prematurely change position and provide a premature shifting of the main valve, such that the piston assembly merely oscillates through an unduly short stroke length.

The other basic type of valve mechanism is exemplified in my co-pending application entitled "Oil Well Pump," filed October 9, 1959, Serial No. 845,571, now Patent No. 2,943,576. This latter type of valve mechanism includes only what may be considered a main valve which is physically unseated at the opposite ends of the movement of the piston assembly, but includes choking elements on the valve for controlling the application of fluid pressures to the valve after the valve is unseated for hydraulically shifting the valve from one operating position to another. Such a valve mechanism is simple in construction and has been found exceptionally efficient in many operating environments. However, the mechanical unseating of the valve possesses some inherent disadvantages. Since the amount of mechanical forces which can be applied to the valve is limited by the physical strength of the actuating members for the valve, the force with which the main valve may be held on its operating seats is also limited. Furthermore, the magnitude of the hydraulic forces imposed on the valve after it is unseated are also related to the force with which the valve can be held on either of its seats. As a result, any foreign matter which may become trapped between cooperating surfaces of the valve and the piston assembly will tend to hold the valve in an intermediate and inoperative position. Also, the forces applied on the valve limit the speed with which the valve is shifted at the end of a stroke of the piston assembly, such that the unseating of the valve must take place a short time prior to the end of a stroke. Therefore, under unusual operating conditions, the pump sometimes fails to move through its maximum stroke length, which reduces the overall efficiency of the pump unit.

The present invention contemplates a novel pump unit which may be utilized in substantially any pumping environment. The pump unit includes a novel valve assembly comprising a main valve and two pilot valves. One of the pilot valves controls the application of fluid pressure to the main valve at the end of one stroke of the unit and the other pilot valve controls the application of fluid pressure to the main valve at the end of the other stroke of the unit. Since each pilot valve has only one operating position, the pilot valves may be easily retained in their inoperative positions during the major portion of the cycle of operation of the unit and will not be affected by abnormal pressure conditions in the motor or engine end of the unit. Also, since the main valve is unseated and shifted solely by the application of fluid pressures controlled by the pilot valves, the effective pressure areas of the main valve may be of sufficient size to securely hold the main valve in a desired operating position and to assure that the main valve will be shifted from one operating position to another. Therefore, the operation of the valve mechanism will be substantially unaffected either by foreign matter entering the unit, as by means of dirty power oil, or by varying pressure conditions in the motor end of the unit. In a preferred construction, at least one of the pilot valves is in the form of a ball type valve which may be constructed of minimum size for controlling the application of maximum fluid pressures on the main valve and yet will have a minimum resistance against unseating as the piston assembly reaches the end of a stroke.

An important object of this invention is to provide a subsurface fluid-operated pump unit which will operate efficiently in substantially all environments.

Another object of this invention is to provide a subsurface fluid-operated pump unit which will not be rendered inoperative by a normal amount of foreign matter in the high pressure fluid used for operating the unit.

Another object of this invention is to provide a novel valve mechanism for a fluid motor wherein the minimum force is required for actuating the pilot valves of the mechanism.

A further object of this invention is to provide a novel valve mechanism for a fluid motor utilizing a main valve which will be held on its operating seats or in its operating positions with maximum forces and will be shifted between its operating positions with the maximum forces, but wherein the minimum physical forces are imposed on the valve mechanism.

A more specific object of this invention is to provide a valve mechanism for a fluid motor utilizing two pilot valves and wherein the pilot valves will not be inadvertently shifted or actuated by abnormal pressure conditions in the motor.

A still further object of this invention is to provide a subsurface fluid-operated pump unit which is simple in construction, may be economically manufactured, may be easily repaired and which will have a long service life.

Other objects and advantages of the invention will be evident from the following detailed description, when read in conjunction with the accompanying drawings which illustrate my invention.

In the drawings:

FIGURE 1A is a vertical sectional view through the engine or motor end of a pump unit constructed in accordance with this invention.

FIGURE 1B is a continuation of the pump unit from the lower end of FIG. 1A and is a vertical sectional view through the pump end of the unit.

FIGURE 2 is a vertical schematic sectional view through the engine end of the pump unit illustrating the position of the valve mechanism at the end of the downstroke of the unit.

FIGURE 3 is a view similar to FIG. 2 illustrating the position of the valve mechanism at the beginning of the upstroke of the unit.

FIGURE 4 is another view similar to FIG. 2 illustrating the position of the valve mechanism during a normal upstroke of the unit.

FIGURE 5 is still another view similar to FIG. 2 illustrating the position of the valve mechanism at the end of the upstroke of the pump unit.

Referring to the drawings in detail, and particularly FIGS. 1A and 1B, reference character 10 generally designates a pump unit constructed in accordance with this invention and which generally comprises a fluid-operated motor 12 and a pump 14 connected to the lower end of the fluid motor in tandem relation with the fluid motor. The motor 12 comprises a cylinder 16 having a cap or head 18 threadedly secured on the upper end 20 thereof and having its lower end 22 threadedly secured in a counterbore 24 of a middle plug 26. The middle plug 26 forms the lower head for the motor cylinder 16 and the upper head for the pump cylinder 28. It will be observed in FIG. 1B that the upper end 30 of the pump cylinder 28 is threadedly secured in a counterbore 32 formed in the lower end of the middle plug 26.

A standing valve assembly, generally designated by reference character 34, is secured on the lower end 36 of the pump cylinder 28 to control the flow of fluid from a well bore (not shown) into the lower end of the motor cylinder 28 in a manner common to the art. In this connection it may also be noted that the pump unit 10 is of a diametrical size for insertion in a well bore at the level of the well fluid in the well bore for pumping this well fluid to the top of the well in a manner common to the

art. The standing valve assembly 34 comprises a tubular body 38 having an upwardly facing valve seat 40 therein to receive a valve member 42. The valve member 42 is provided with a stem 44 slidably positioned in a tubular guide 46 to retain the valve member 42 concentric with the valve seat 40. The upward, opening movement of the valve member 42 is limited by a suitable perforated stop 48. It will be apparent that the valve member 42 moves upwardly to an open position when the pressure in the lower end of the pump cylinder 28 is less than the pressure below the valve member. Suitable threads 50 may be provided in the lower end portion of the valve body 38, if desired, for supporting a gas anchor (not shown) on the lower end of the pump unit 10 in the usual fashion.

20 A tubular pump piston 52 is reciprocally disposed in the pump cylinder 28 and is provided with a plurality of piston rings 54 around the outer periphery thereof which slidably and sealingly engage the inner periphery of the pump cylinder 28 during reciprocation of the pump piston. A seating member 56 is threadedly secured in the lower end of the pump piston 52 and is provided with an upwardly facing annular seating area 58 at the upper end thereof to receive a valve member 60. The valve member 60 is provided with a stem 62 extending downwardly therefrom and slidably received in a tubular guide 64 formed in the valve seating member 56. It will therefore be apparent that the valve member 60 moves upwardly when the pressure below the piston 52 is higher than the pressure above the piston 52, and vice versa, such that the pump 14 is what is commonly known in the art as a single-acting pump. It may also be noted that the upstroke of the pump piston 52 is the working stroke.

25 A hollow connecting rod 66 is connected to the upper end of the pump piston 52 and extends vertically upward through the middle plug 26 into connection with the motor 12, as will be described. It should be noted here, however, that the lower end 68 of the hollow connecting rod 66 is in communication with the interior of the piston 52 through a bore 70 to provide a continuous passageway from the connecting rod 66 through the upper end portion of the piston 52 into the upper end portion of the pump cylinder 28.

30 Suitable packing 72 is retained in a bore 74 in the central portion of the middle plug 26 to provide a seal around the connecting rod 66. The packing 72 is held in fluid-tight engagement with the outer periphery of the connecting rod 66 and the walls of the bore 74 by a suitable retaining nut 76. An outlet 78 is formed through one side of the middle plug 26 below the packing 72 and in communication with the upper end portion of the pump cylinder 28. Therefore, all fluids pumped by the pump unit 14 will be discharged through the outlet 78. The outlet 78 in turn communicates with a suitable conduit (not shown) extending from the pump unit 10 upwardly to the top of the well bore in which the pump unit is installed for recovery of the fluids pumped by the pump 14.

35 An inlet 80 (FIG. 1A) is also formed through one side of the middle plug 26, but is positioned above the packing 72 to direct high pressure power fluid into the lower end of the motor cylinder 16 for operation of the motor 12, as will be described. It will be understood that the inlet 80 communicates with a suitable conduit (not shown) extending from the top of the well bore in which the pump unit is installed, such that high pressure fluid may be pumped downwardly into the lower end of the pump cylinder 16 for operation of the motor 12.

40 A motor piston assembly 82 is reciprocally disposed

in the motor cylinder 16 and includes a piston element 84 having a plurality of piston rings 86 secured around the periphery thereof in sliding and sealing contact with the inner periphery of the cylinder 16. A piston extension 88 is threadedly secured to the lower end of the piston element 84 and is in turn threadedly secured to the upper end 90 of the hollow connecting rod 66, such that reciprocation of the motor piston assembly 82 will be transferred to the pump piston 52. It may also be noted in this connection that since the connecting rod 66 extends from the lower end of the motor piston assembly 82, the downwardly facing areas of the assembly 82 are smaller than the upwardly facing areas of the piston assembly, to provide what is commonly known in the art as a differential area piston.

A main valve chamber 92 is provided in the central portion of the piston element 84 and extends along the longitudinal center of the piston element 84 to be parallel with the direction of movement of the piston assembly 82. A valve seating member 94 extends around a medial portion of the valve chamber 92 and is provided with an upwardly facing annular seating area 96 to receive a mating seating area 98 of the main valve 100. The seating member 94 is provided with a suitable sealing ring 102 around the periphery thereof and is held in operating position against an upwardly facing shoulder 104 in the piston element 84 by an insert 106 which is in turn held in the piston element by a cap member 108 threadedly secured in the upper end of the piston element.

The main valve 100 is an elongated member of a size to provide a metal-to-metal seal with the walls of the medial portion of the valve chamber 92 and having sets of piston rings 110 and 112 on the lower and upper ends thereof, respectively. The lower piston rings 110 are secured around the respective end of the valve 100 by suitable spacer rings 114 which are in turn held in contact with one another and in contact with a downwardly facing annular shoulder 116 by a suitable snap ring 118. These lower piston rings 110 form an enlarged head portion 119 which slidably contacts the walls of the lower, enlarged portion 120 of the valve chamber 92.

A port 122 is formed transversely through the piston element 84 below the lower end of the main valve 100 in communication with the enlarged portion 120 of the valve chamber 92 to form a portion of a high pressure passageway through the piston assembly 82, as will be more fully hereinafter set forth. A bore 124 extends longitudinally through the main valve 100 to provide a continuation of the high pressure passageway. It may also be noted that a small port or aperture 126 is formed transversely through the wall of the main valve 100 directly above the lower head portion 119 to provide communication between the valve bore 124 and the enlarged portion 120 of the valve chamber 92, for purposes to be described.

The upper piston rings 112 of the main valve 100 are supported in mating grooves around an enlarged head portion 128 of the valve 100 to slidably contact the walls of an upper enlarged portion 130 of the valve chamber 92 formed by the spacer 106. It will be observed that the downwardly facing seating area 98 of the main valve 100 is formed around the lower end portion of this head 128 to mate with the valve seat 94.

The medial portion 132 of the main valve 100 between the head 128 and the main body portion of the valve which is slidably sealed in the valve chamber 92 is reduced in diameter to extend loosely through the valve seat 94. This reduced diameter portion 132 is provided for the communication of ports 134 and 136 provided directly below and above the valve seat 94 in one position of the valve 100, as will be described. The lower port 134 communicates with a passageway 138 extending vertically through the piston element 84 and the piston extension 88.

The passageway 138 in turn communicates with the upper end of the hollow connecting rod 66 through a suitable chamber 140 to form what may be considered an exhaust passageway which conducts spent operating or power fluid from the upper end of the motor cylinder 16 downwardly into the connecting rod 66. The upper port 136 extends through the spacer 106 and the wall of the piston element 84 into communication with the upper end of the motor cylinder 16.

10 An upwardly facing annular seating area 142 is formed at the upper end of the main valve 100 around a counterbore formed at the upper end of the valve bore 124 to mate with a downwardly facing seating area 146 formed on the cap member 108 at the upper end of the piston element 84. The seating area 146 is formed around a projection extending below the lower end of the cap member 108 into a counterbore 148 formed in the upper end of the spacer 106. A plurality of ports 150 are formed in the cap member 108 from the lower end thereof around 15 the seating area 146 to a common passageway 152 communicating with the upper end of the cap member 108 and the upper end portion of the motor cylinder 16. It will be apparent that when the main valve 100 is in the position shown in FIG. 1A, the passageway 152 and 20 ports 150 communicate with the counterbore 148, the valve bore 124, and the port 122 to form what is called herein the high pressure passageway, such that high pressure fluid may flow from the lower end portion of the motor cylinder 16 through the piston assembly 82 into 25 the upper end of the motor cylinder. In this connection it may also be noted that the low pressure or exhaust passageway 138 is closed between the ports 134 and 136 by the cooperation of the valve seating areas 96 and 98, such that fluid may not be exhausted from the upper end 30 portion of the motor cylinder 16 into the hollow connecting rod 66.

35 A ball type pilot valve 154 is positioned in a counterbore 156 formed in the lower end of the cap member 108 concentrically inside of the seating area 146. The ball type valve 154 cooperates with a downwardly facing seating area 158 formed between the counterbore 156 and a bypass port 160 which communicates with the passageway 152. It will therefore be apparent that the ball pilot valve 154 will normally be retained on the seat 158 by the 40 action of high pressure fluid in the upper end of the valve bore 124 acting through the counterbore 156. The ball valve 154 is unseated by a rod 162 suitably secured to the upper cylinder head 118 when the piston assembly 82 reaches the end of its upstroke. The rod 162 has a reduced lower end portion 164 of a size to be received in the bypass port 160 to contact the ball valve 154 and physically unseat this ball valve. It may also be noted that a suitable retainer or spider 166 is mounted in the counterbore 156 below the ball valve 154 to prevent the ball valve 154 from being completely removed from the counterbore 156 when unseated by the rod 162. The stop 166 is perforated or otherwise suitably constructed so as not to interfere with the transfer of fluid pressure therethrough against the ball valve 154.

60 Another pilot valve 168 is slidably disposed in a tubular insert 170 secured between the piston element 84 and the piston extension 88 and extends through a bore 172 in the piston extension 88. The insert 170 is sealed in the lower end of the enlarged portion 120 of the valve chamber 92 and in the piston extension 88 by suitable sealing rings 174 to prevent leakage from the lower end of the valve chamber. The pilot valve 168 is an elongated member having a cylindrical head 176 formed on the upper end thereof and continuously exposed to the pressure of the fluid in the lower portion of the valve chamber 92. The head 176 is of a size to slidably fit in the lower end of the main valve bore 124 to control the application of fluid pressure to the main valve at the lower end of the downstroke, as will be described. Also, a flange 70 178 extends outwardly around the pilot valve 168 directly

below the head portion 176 to limit the movement of the pilot valve into the main valve, as will be described. A compression spring 180 extends around the pilot valve 168 between the insert 170 and a nut 182 threaded onto the lower end of the pilot valve, such that the spring 180 constantly urges the pilot valve 168 downwardly to move the cylindrical head portion 176 in a direction away from the main valve 100.

The pilot valve 168 is actuated by a suitable harness 184 when the piston assembly 82 reaches the lower end of its downstroke. The harness 184 comprises a ring 186 fitting loosely around the piston extension 88 arranged to contact an upwardly facing shoulder 188 at the lower end of the middle plug counterbore 24 when the piston assembly reaches the end of its downstroke. A bar 190 is secured to the upper end of the harness ring 186 by a suitable screw 192 and extends inwardly through a mating slot 194 in the piston extension 88 to contact the nut 182 on the lower end of the pilot valve 168. It will be apparent that when the harness 184 contacts the upwardly facing shoulder 188 at the lower end of the motor cylinder 16, the pilot valve 168 will be moved upwardly relative to the piston assembly upon any further downward movement of the piston assembly. The harness 184 is normally in its lower position resting at the lower end of the slot 194 by the action of gravity and, as previously noted, the spring 180 normally retains the pilot valve 168 in its lowermost position in contact with the harness 184 as illustrated in FIG. 1A.

Operation

As previously indicated, high pressure power fluid, which is normally in the form of clean oil, is continuously fed through the inlet 80 into the lower end of the motor cylinder 16 to act on the downwardly facing areas of the piston assembly 82. In the position of the main valve 100 shown in FIG. 1A, this high pressure power fluid also flows through the port 122, the valve bore 124, the ports 150 and passageway 152 to act on the upwardly facing areas of the piston assembly 82. Since the upwardly facing areas of the piston assembly 82 provide a larger effective area than the downwardly facing areas of the piston assembly (by reason of the connecting rod 66 extending from the lower end of the piston assembly), the net hydraulic force acting on the piston assembly 82 will be in a downward direction to produce a downstroke for the pump unit 10. During this downstroke it will also be observed that the pilot valve 168 will be held in its lowermost position by the action of the spring 180 and by the action of gravity. The port 122 which provides the application of fluid pressure across the upper end of the lower pilot valve 168 is of appreciable size and will produce no appreciable pressure drop for high pressure fluid flowing therethrough. Therefore, the fluid pressure forces acting on the pilot valve 168 will be balanced, regardless of the speed of the downstroke or any other commonly encountered abnormal pump operation, such that the pilot valve 168 will remain in the position shown in FIG. 1A. The upper pilot valve 154 is retained on its seat 158 by the action of high pressure fluid flowing through the valve bore 124 and through the upper end of the valve chamber 92. However, on the downstroke of the pump unit, the power fluid flows around the pilot valve 154 (through the ports 150) and it is immaterial whether or not the pilot valve 154 is retained on its seat 158.

Near the end of the downstroke of the pump unit, the harness 184 contacts the upwardly facing shoulder 188 in the middle plug 26 (see FIG. 2) and moves the lower pilot valve 168 upward relative to the piston assembly 82. As soon as the cylindrical head portion 176 of the pilot valve 168 first enters the lower end of the valve bore 124, flow of the power fluid through the valve bore 124 is restricted and a substantial pressure drop occurs between the lower end of the main valve chamber 92 and

the valve bore 124 immediately above the pilot valve cylindrical head 176. As a result, the cylindrical head 176 will be "sucked" into the valve bore 124 to further restrict the flow of high pressure fluid into the valve bore 124. Since the piston assembly 82 is moving downwardly at this time, the pressure of the fluid standing in the valve bore 124, the upper end portion of the main valve chamber 92 and in the upper end of the motor cylinder 16 is reduced to a pressure below the pressure of the power fluid. Thus, the force acting downwardly on the upper end of the main valve 100 and the force acting downwardly on the lower head portion 119 of the main valve (by reason of the port 126) are reduced, while the upwardly acting force imposed by the power fluid on the lower head 119 of the main valve 100 is continued. As a result, the net force acting on the main valve 100 will be in an upward direction to shift the main valve 100 off of the seat 96 and onto the seat 146, as illustrated in FIG. 3.

In analyzing the function of the valve mechanism at the end of the downstroke, it will be apparent that the pilot valve 168 is first moved by physical contact with the harness 184, and then the upward movement of the pilot valve 168 is continued by hydraulic forces. As a result, the pilot valve 168 actually moves to a position above the harness 184 when the cylindrical head portion 176 is fully inserted in the valve bore 124. It should also be noted that under the dynamic conditions existing during operation of the piston assembly 82, the lower pilot valve 168 merely controls the application of fluid pressures on the main valve 100 and provides a hydraulic shifting of the main valve. The hydraulic forces acting on the main valve 100 are changed immediately upon entry of the cylindrical head portion 176 into the lower end of the valve bore 124 to initiate the shifting of the main valve. The cylindrical head portion 176 will be moved on into the valve bore 124 by hydraulic forces until the flange 178 on the pilot valve 168 contacts the lower end of the main valve. However, this physical contact takes place after the hydraulic forces acting on the valve 100 are changed and actually does not function to shift the main valve. Since the pressure above the cylindrical head portion 176 is then less than the upwardly acting pressure forces on the pilot valve 168, the pilot valve 168 will tend to move upwardly with the main valve 100 against the action of the spring 180. As a result, some portion of the cylindrical head 176 remains in the valve bore 124 during the complete shifting of the main valve from the seat 96 to the seat 146, such that the net hydraulic force acting on the main valve 100 will continue to be in an upward direction while the main valve is fully seated on the seat 146. The final position of the pilot valve 168 during a seating of the main valve 100 on the seat 146 is illustrated in FIG. 3. As soon as the main valve 100 is shifted to its upper position as shown in FIG. 3, the pilot valve 168 is moved back downwardly by action of the spring 180 into contact with the harness 184, as shown in FIG. 4.

When the lower pilot valve 168 is completely removed from the valve bore 124, the power fluid has access to the valve bore 124 to act in an upward direction on the upper pilot valve 154 and positively close the bypass passageway 160. It will be recalled that at this time the pressure above the piston assembly 82 is less than power fluid pressure and the pilot valve 154 will be retained on its cooperating seat 158 by a pressure differential acting across the area of the seat 158. When the main valve 100 is seated on the seat 146 and when the bypass passageway 160 is closed by the upper pilot valve 154, the hydraulic force acting downwardly on the upper end of the main valve will be substantially less than the force acting upwardly across the lower end of the main valve. Also, power fluid is communicated through the port 126 across the upwardly facing area of the lower main valve head 119, but this area is small

compared with the downwardly facing lower end of the main valve, such that the main valve will be positively held on the upper seat 146 during the upstroke of the pump unit.

As the main valve 100 is being shifted upwardly and after the main valve is seated on the seat 146, the upward flow of power fluid through the valve bore 124 is discontinued and the exhaust passageway 138 is immediately opened to provide a net hydraulic force on the piston assembly 82 in an upward direction, such that the movement of the piston assembly 82 is reversed and the pump unit moved on an upstroke. It may also be noted that at the completion of the downstroke and during the shifting of the main valve 100, the lower end of the piston extension 88 moves into a counterbore 200 formed in the middle plug 26 to provide a dashpot action and further assure that the piston assembly 82 will not knock against the middle plug 26 and cause damage to the pump unit. The slow reversal provided by this dashpot action and by fluid being fed into the lower end of the motor cylinder 16 allows sufficient time for the pump traveling valve 60 to close, thus minimizing leakage through the pump piston 52 and increasing the service life of the traveling valve seat 58.

During the upstroke of the pump unit, as shown in FIG. 4, fluid in the upper end of the motor cylinder 16 is exhausted downwardly through the passageway 138, as previously indicated, and this exhausting fluid enters the hollow connecting rod 66. Therefore, the exhausting power fluid will be co-mingled with the well fluid being forced upwardly through the pump cylinder 28 by the action of the pump piston 52 and will be discharged through the outlet 78 for conduction to the top of the well.

As the piston assembly 82 reaches the end of the upstroke, as illustrated in FIG. 5, the rod 162 is received in the passageway 152 and the bypass 160 to contact the upper ball type pilot valve 154. As a result, the valve 154 is removed from its seat 158 to provide communication from the valve bore 124 through the bypass 160 to the ports 150 and increase the hydraulic force acting in a downward direction on the upper end of the main valve 100. This downwardly acting force, in combination with the action of the power fluid across the upper end of the lower main valve head 119, provides a net downwardly acting force on the main valve 100 to shift the main valve back downwardly onto the seat 96 in the position illustrated in FIG. 1A. It should also be noted that the upwardly facing area of the upper end of the main valve 100 around the seating area 142 is substantially larger than the cross sectional area of the pilot valve seat 158. Therefore, the mechanical force applied on the ball valve 154 by the rod 162 is substantially less than the downwardly acting force obtained by the application of the power fluid through the bypass passageway 160 and ports 150 against the upper end of the main valve. Furthermore, the ball valve 154 and its cooperating seat 158 may be of minimum size to minimize the force required to be applied by the rod 162 to unseat the valve, to in turn minimize the strength of materials required in the pump construction.

As soon as the main valve 100 is shifted downwardly onto the seating area 96, the exhaust passageway 138 is closed and power fluid is admitted to the upper end of the motor cylinder 16 through the valve bore 124, ports 150 and passageway 152 to again reverse the movement of the piston assembly 82 and provide a downstroke of the pump unit. It may also be noted that since the rod 162 occupies an appreciable portion of the area of the passageway 152 at the end of the upstroke and the beginning of the downstroke, the movement of the piston assembly 82 is slowly reversed and the standing valve 42 of the pump 14 will have sufficient time to close prior to the initiation of the downstroke, such that a minimum back-flow of well fluid downwardly from the pump cyl-

inder 28 through the standing valve assembly 34 will occur. This slow reversal of the pump stroke greatly facilitates the operation of the standing valve 42 and minimizes the cutting out of the standing valve seat 40 by the leakage of the dirty well fluid therethrough.

In analyzing the function of the valve mechanism, it will be apparent that both of the pilot valves 154 and 168 are mechanically actuated and then control the application of fluid pressures on the main valve 100. The lower pilot valve 168 is actuated at the end of the downstroke to produce a net hydraulic force on the main valve 100 in an upward direction to shift the main valve upwardly onto the seat 146. At the end of the upstroke, the pilot valve 154 is mechanically actuated by the rod 162 to produce a net hydraulic force on the main valve 100 acting in a downward direction to move the main valve downwardly onto the seating area 96. Since the main valve 100 is both unseated and then shifted solely by hydraulic forces, the pressure areas of the main valve may be designed to provide substantial hydraulic forces for unseating the valve, shifting the valve and holding the valve on its respective seats. Furthermore, the pressure areas of the main valve 100, and the actual forces applied on the main valve for the unseating, shifting and holding operations are not limited by either the sizes or strengths of the pilot valves. The upper pilot valve 154 and the actuating rod 162 may be of economical construction, since the only force applied on the pilot valve 154 is that force necessary to overcome a pressure differential acting across the area of the pilot valve seat 158. The mechanical unseating of the ball valve 154 results in a substantial hydraulic force being applied to the main valve 100. The lower pilot valve 168 is moved mechanically only against the action of the spring 180, such that the harness 184 will have minimum strength requirements. Here again, the mechanical force applied to the lower pilot valve 168 is extremely small compared with the resulting hydraulic forces imposed on the main valve 100 for the unseating, shifting and holding of the main valve.

The above-described functional requirements for the pilot valves 154 and 168 not only provide an economical construction having minimum strength requirements, but also assure that the piston assembly 82 will complete its up and down strokes under substantially all operating conditions. The appreciable hydraulic forces imposed on the main valve 100 will minimize the possibility of the main valve being stuck in an inoperative position by the accumulation of foreign matter from dirty power fluid in the valve chamber 92. Also, since substantial hydraulic forces are imposed on the main valve by minimal physical actuation of the pilot valves 154 and 168, the actuating mechanisms comprising the rod 162 and the harness 184 may be designed to provide a shift of the main valve 100 only when each stroke of the piston assembly 82 is substantially complete. In other words, the valve mechanism and the actuators 162 and 184 may be designed to shift the main valve when the piston assembly 82 is within a few thousandths of an inch from the respective end of the motor cylinder 16. The fast response of the main valve 100 to the application of the hydraulic forces provides an immediate control of the flow of the power fluid to the piston assembly 82 to reverse the piston assembly movements. As a result, the present pump unit will be particularly effective under abnormal operating conditions, such as when the pump unit is used in gassy wells or is driven by dirty power fluid, to provide a pump unit having universal utility.

From the foregoing it will be apparent that the present invention provides a novel subsurface fluid-operated pump unit which is simple in construction, may be economically manufactured, may be easily repaired and which will have a long service life. The present pump unit will have substantially more universal utility than present-day subsurface fluid-operated pumps. The pump

unit will not tend to "cavitate" in gassy well conditions and each stroke of the pump unit will be completed before the next stroke is undertaken to assure the maximum efficiency in a pumping operation. Also, the reversals of the pump unit will be retarded such that the valves in the pump end of the unit will have the maximum service life. The valve mechanism of the motor end of the unit is simply constructed, will not be affected by abnormal pumping conditions and may be economically constructed.

Changes may be made in the combination and arrangement of parts or elements as heretofore set forth in the specification and shown in the drawings, it being understood that changes may be made in the precise embodiment disclosed herein without departing from the spirit and scope of the invention as defined in the following claims.

I claim:

1. A subsurface fluid-operated pump unit, comprising: a motor cylinder member; a motor piston member reciprocally disposed in the motor cylinder member and responsive to fluid pressures in the opposite ends of the motor cylinder member for reciprocation in the motor cylinder member; a main valve chamber in one of said members; a high pressure passageway intersecting the main valve chamber and communicating with at least one end of the motor cylinder member; an exhaust passageway intersecting the main valve chamber and communicating with at least one end of the motor cylinder member; valve seats in the main valve chamber in the high pressure and exhaust passageways; a main valve disposed in the main valve chamber and being responsive to the application of fluid pressures thereto for reciprocation in the main valve chamber to alternately seat on the valve seats and control the flow of fluid to and from at least one end of the motor cylinder member; a pair of pilot valves in the high pressure passageway for controlling the application of high pressure fluid to the main valve for shifting the main valve off of and on to said seats; separate actuating means at the opposite ends of one of said members arranged to actuate one of the pilot valves when the motor piston member reaches one end of the motor cylinder member and actuate the other pilot valve when the motor piston member reaches the opposite end of the motor cylinder member; a pump cylinder connected in tandem relation to the motor cylinder member and having an inlet and an outlet, and a pump piston reciprocally disposed in the pump cylinder and connected to the motor piston member.

2. A subsurface fluid-operated pump unit as defined in claim 1 wherein one of said pilot valves comprises a ball type valve and cooperating seat with the seat facing high pressure fluid in the high pressure passageway such that the ball type valve is continuously urged onto the seat by the high pressure fluid, one of said actuating means comprises a rod positioned to knock said ball type valve off of its cooperating seat when the motor piston member reaches the respective end of the motor cylinder member, and characterized further to include a bypass passageway extending from said ball type valve seat to the main valve chamber for applying high pressure fluid against the main valve when the ball type valve is removed from its seat.

3. A subsurface fluid-operated pump unit as defined in claim 1 wherein said main and pilot valves are carried by the motor piston member in alignment along the axis of movement of the motor piston member, and said main valve is tubular in form with the bore therethrough forming a portion of said high pressure passageway.

4. A subsurface fluid-operated pump unit as defined in claim 3 wherein the main valve chamber is elongated, said pilot valves are positioned at the opposite ends of the main valve chamber, one of said pilot valves comprises a ball valve seat facing the opposite end of the main valve chamber and a ball type valve cooperating with said ball valve seat, one of the seats for the main

valve comprises an annular seating area arranged concentrically around said ball valve seat to receive the respective end of the main valve, and characterized further to include a bypass passageway from said ball type valve seat around said concentric main valve seat for directing high pressure fluid against the respective end of the main valve when the main valve is seated on said concentric seat and said ball type valve is actuated.

5. A subsurface fluid-operated pump unit as defined in claim 4 wherein the other of said pilot valves comprises an elongated element reciprocally supported in the motor piston member with one end thereof projecting into the main valve chamber, said one end of said other pilot valve being in the form of a cylindrical head of a size to slidably fit the adjacent end of the main valve, and one of said actuating means comprises a harness carried by the motor piston member in a position to contact said other pilot valve and move said cylindrical head into the adjacent end of the main valve and control the application of fluid pressure on the main valve when the motor piston member reaches one end of the motor cylinder member.

6. A subsurface fluid-operated pump unit, comprising: a motor cylinder; a motor piston assembly reciprocally disposed in the motor cylinder and having a large end and a small end; a supply of high pressure power fluid; means providing constant communication between said supply and the end of the motor cylinder associated with the small end of the motor piston assembly to constantly apply power fluid against said small end and urge the motor piston assembly in one direction in the motor cylinder; a main valve chamber in the motor piston assembly; a first passageway intersecting the main valve chamber providing communication between said supply and the end of the motor cylinder associated with the large end of the motor piston assembly to direct power fluid against the large end of the motor piston assembly and urge the motor piston assembly in an opposite direction; an exhaust passageway intersecting the main valve chamber and communicating with the end of the motor cylinder associated with the large end of the motor piston assembly for exhausting power fluid from the end of the motor cylinder associated by the large end of the motor piston assembly and provide movement of the motor piston assembly in said one direction; a valve seat in the main valve chamber in each of the first and exhaust passageways, said valve seats being positioned in spaced relation; a main valve reciprocally disposed in the main valve chamber for alternately closing said valve seats and controlling the flow of power fluid to and from the end of the motor cylinder associated with the large end of the motor piston assembly; a first pilot valve carried by the motor piston assembly and cooperating with said first passageway to control the application of power fluid pressure to the main valve and hydraulically shift the main valve from one of said seats to the other seat; a second pilot valve carried by the motor piston assembly and cooperating with said first passageway to control the application of power fluid pressure to the main valve and hydraulically shift the main valve from said other valve seat to said one valve seat; means for actuating one of said pilot valves when the motor piston assembly reaches one end of the motor cylinder; separate means for actuating the other of said pilot valves when the motor piston assembly reaches the opposite end of the motor cylinder; a pump cylinder connected in tandem relation to the motor cylinder and having a fluid inlet and outlet; a pump piston assembly reciprocally disposed in the pump cylinder, and a connecting rod secured to the pump piston assembly and the motor piston assembly to reciprocate the pump piston assembly simultaneously with the motor piston assembly.

7. A subsurface fluid-operated pump unit as defined in claim 6 wherein the main valve chamber is an elongated chamber extending along the axis of movement of the motor piston assembly, said main valve is tubular in form

and the bore therethrough forms a portion of said first passageway, and said pilot valves are positioned at the opposite ends of the main valve chamber.

8. A subsurface fluid-operated pump unit as defined in claim 7 wherein one of said pilot valves comprises a ball valve seat facing the opposite end of the main valve chamber and a ball type valve cooperating with said seat, one of said main valve seats comprises an annular seating area positioned at the end of the main valve chamber associated with the ball valve and arranged concentrically around said ball valve seat, said main valve having a seating area around the inner periphery of the end thereof associated with the ball type valve to mate with said annular seating area in one position of the main valve, a bypass passageway extending from said ball valve seat, and said first passageway being extended from said bypass passageway around said annular seating area to apply high pressure fluid pressure on the end of the main valve when the main valve is seated on said annular seating area and said ball valve seat is open.

9. A subsurface fluid-operated pump unit as defined in claim 7 wherein one of said pilot valves comprises an elongated element reciprocally supported in the motor piston assembly in alignment with the main valve and with the opposite ends thereof exposed to said high pressure fluid, one end of said elongated element being positioned in the respective end of the main valve chamber, said one end of said elongated element being in the form of a cylindrical head of a size to slidingly fit in the respective end of the main valve, and said actuating means associated with said elongated element comprises a harness carried by the motor piston assembly in a position to contact one end of the motor cylinder when the motor piston assembly reaches said end for contacting said elongated element and moving said cylindrical head into the respective end of the main valve for controlling the application of fluid pressure on the main valve.

10. A reciprocating type fluid motor, comprising a cylinder member; a piston member reciprocally disposed in the cylinder member and responsive to fluid pressures in the opposite ends of the cylinder member for reciprocation in the cylinder member; a main valve chamber in one of said members; a high pressure passageway intersecting the main valve chamber and communicating with at least one end of the cylinder member; an exhaust passageway intersecting the main valve chamber and communicating with at least one end of the cylinder member; valve seats in the main valve chamber in the high pressure and exhaust passageways; a main valve disposed in the main valve chamber and being responsive to the application of fluid pressure thereto for reciprocation in the main valve chamber to alternately seat on the valve seats and control the flow of fluid to and from at least one end of the cylinder member; a pair of pilot valves in the high pressure passageway for controlling the application of high pressure fluid to the main valve for shifting the main valve off of and onto said seats; and separate actuating means at the opposite ends of one of said members arranged to actuate one of the pilot valves when the piston member reaches one end of the cylinder member and actuate the other pilot valve when the piston member reaches the opposite end of the cylinder member.

11. A fluid motor as defined in claim 10 wherein one of said pilot valves comprises a ball type valve and cooperating seat with the seat facing high pressure fluid in the high pressure passageway such that the ball type valve is continuously urged onto the seat by high pressure fluid, one of said actuating means comprises a rod positioned to knock the ball type pilot valve off of its cooperating seat when the piston member reaches the respective end of the cylinder member, and characterized further to include a bypass passageway extending from said ball type valve seat to the main valve chamber for applying high pressure fluid against the main valve when the ball type valve is removed from its seat.

12. A fluid motor as defined in claim 10 wherein said main valve is tubular in form and the bore therethrough forms a portion of the high pressure passageway, one of said pilot valves includes a cylindrical head of a size to slidingly fit in one end of the main valve, said last-mentioned pilot valve being reciprocally supported in alignment with and adjacent to one end of the main valve for movement of said cylindrical head into the main valve upon actuation thereof by one of said actuating means to control the application of fluid pressure on the main valve and shift the main valve, and characterized further to include a spring anchored to said last-mentioned pilot valve urging said pilot valve in a direction away from the main valve.

13. A fluid motor as defined in claim 10 wherein said main and pilot valves are carried by the piston member in alignment along the axis of movement of the piston member, and said main valve is tubular in form with the bore therethrough forming a portion of said high pressure passageway.

14. A fluid motor as defined in claim 13 wherein the main valve chamber is elongated, said pilot valves are positioned at the opposite ends of the main valve chamber, one of said pilot valves comprises a ball valve seat facing the opposite end of the main valve chamber and a ball type valve cooperating with said ball valve seat, one of the seats for the main valve comprises an annular seating area arranged concentrically around said ball valve seat to receive a seating area formed on the respective end of the main valve, said last-mentioned seating area being formed around the inner periphery of the main valve, and characterized further to include a bypass passageway from said ball type valve seat around said concentric main valve seat for directing high pressure fluid against the respective end of the main valve when the main valve is seated on said concentric seat and said ball type valve is actuated.

15. A fluid motor as defined in claim 14 wherein the other of said pilot valves comprises an elongated element reciprocally supported in the piston member with one end thereof projecting into the main valve chamber, said one end of said other pilot valve being in the form of a cylindrical head of a size to slidingly fit in the adjacent end of the main valve, and one of said actuating means comprises a harness carried by the piston member in a position to contact said other pilot valve and move said cylindrical head into the adjacent end of the main valve and control the application of fluid pressure on the main valve when the piston member reaches one end of the cylinder member.

16. A reciprocating type fluid motor, comprising: a cylinder; a piston assembly reciprocally disposed in the cylinder and having a large end and a small end; a supply of high pressure power fluid; means providing constant communication between said supply and the end of the cylinder associated with the small end of the piston assembly to constantly supply power fluid against said small end and urge the piston assembly in one direction in the cylinder; a main valve chamber in the piston assembly; a first passageway intersecting the main valve chamber providing communication between said supply and the end of the cylinder associated with the larger end of the piston assembly to direct power fluid against the large end of the piston assembly and urge the piston assembly in an opposite direction; an exhaust passageway intersecting the main valve chamber and communicating with the end of the cylinder associated with the large end of the piston assembly for exhausting power fluid from the end of the cylinder associated with the large end of the piston assembly and provide movement of the piston assembly in said one direction; a valve seat in the main valve chamber in each of the first and exhaust passageways, said valve seats being positioned in spaced relation; a main valve reciprocally disposed in the main valve chamber for alternately closing said valve seats and

15

controlling the flow of power fluid to and from the end of the cylinder associated with the large end of the piston assembly; a first pilot valve carried by the piston assembly and cooperating with said first passageway to control the application of power fluid pressure to the main valve and hydraulically shift the main valve from one of said seats to the other seat; a second pilot valve carried by the piston assembly and cooperating with said first passageway to control the application of power fluid pressure to the main valve and hydraulically shift the main valve from said other valve seat to said one valve seat, means for actuating one of said pilot valves when the piston assembly reaches one end of the cylinder, and separate means for actuating the other of said pilot valves when the piston assembly reaches the opposite end of the cylinder.

17. A fluid motor as defined in claim 16 wherein said main valve chamber is an elongated chamber extending along the axis of movement of the piston assembly, said main valve is tubular in form and the bore therethrough forms a portion of said first passageway, and said pilot valves are positioned at the opposite ends of the main valve chamber.

18. A fluid motor as defined in claim 17 wherein one of said pilot valves comprises a ball valve seat facing the opposite end of the main valve chamber and a ball valve cooperating with said seat, one of said main valve seats comprises an annular seating area positioned at the end of the main valve chamber associated with the ball valve and arranged concentrically around said ball valve seat, said main valve having a seating area around the inner periphery of the end thereof facing the ball type valve to mate with said annular seating area in one position of the main valve, a bypass passageway extending from said ball valve seat, and said first passageway

16

being extended from bypass passageway around said annular seating area to apply high pressure fluid pressure on the respective end of the main valve when the main valve is seated on said annular seating area and said ball valve seat is open.

5 19. A fluid motor as defined in claim 18 wherein said actuating means associated with said ball type valve comprises a rod secured to the respective end of the cylinder and being of a size to be received in said first 10 passageway when the piston assembly reaches the respective end of the cylinder for unseating said ball type valve from its cooperating seat.

20 20. A fluid motor as defined in claim 17 wherein one 15 of said pilot valves comprises an elongated element reciprocally supported in the piston assembly in alignment with the main valve and with the opposite ends thereof exposed to said high pressure fluid, one end of said elongated element being positioned in the respective end of the main valve chamber, said one end of said elongated 20 element being in the form of a cylindrical head of a size to slidily fit in the respective end of the main valve, and said actuating means associated with said elongated element comprising a harness carried by the piston assembly in a position to contact one end of the cylinder when 25 the piston assembly reaches said end for contacting said elongated element and moving said cylindrical head into the respective end of the main valve for controlling the application of fluid pressure on the main valve.
